US00D539080S

(12) **United States Design Patent** (10) Patent No.: **US D539,080 S**
Zhiwen et al. (45) Date of Patent: **** Mar. 27, 2007**

(54) **FOOD PROCESSOR**

(75) Inventors: **Liao Zhiwen**, Foshan (CN); **Brian K. Beesley**, Draper, UT (US)

(73) Assignee: **Back to Basics Products, Inc.**, Bluffdale, UT (US)

(**) Term: **14 Years**

(21) Appl. No.: **29/251,616**

(22) Filed: **Jan. 9, 2006**

(51) **LOC (8) Cl.** **31-00**

(52) **U.S. Cl.** **D7/384**

(58) **Field of Classification Search** D7/376-386,
D7/412-414, 665; 99/509-511; 241/30-37.5,
241/101.01-101.02, 166-169.1, 274-278.2,
241/285.1-285.3, 291, 292.1; 366/64-67,
366/98, 197-221, 241-254, 279-292, 341-343,
366/325.94

(57) **CLAIM**

The ornamental design for a food processor, as shown and described.

DESCRIPTION

FIG. 1 is an elevated, perspective view of the food processor in accordance with our invention;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1-7 are for illustrative purposes only and form no part of the claimed design.

1 Claim, 6 Drawing Sheets
